FIRE EXTINGUISHING APPARATUS

Daniel Mapes, Montclair, N. J., assignor to Walter Kidde & Company, Inc., Bloomfield, N. J., a corporation of New York

Application July 14, 1934, Serial No. 735,152

9 Claims. (CL 169—11)

The present invention relates to fire extinguishing apparatus of the type wherein the extinguishing medium is stored in suitable containers under the pressure of its own vapor. The fire extinguishing agent commonly used in these systems is carbonic acid gas which is maintained in liquid form in the containers under the extreme pressure of its vapor and a system of pipes is coordinated with the containers to enable the fluid 5 to be discharged at desired locations where the protection is to be afforded.

Where an installation requires the number of containers to be multiplied greatly, the difficulty of providing a means for effecting discharge from 15 the entire bank or gang of containers simultaneously and effectively is confronted. It has been found that there is a practical limit to the number of containers which can be controlled by direct manual force and the present invention 20 relates to systems wherein the number of containers renders the manual control thereof difficult, if not impossible.

It has been proposed to employ the expansive force of the extinguishing medium itself to effect 25 the release of the extinguishing medium from all of the containers as desired and in such systems, certain containers, known as master-control 30 containers, are set aside to supply the medium to actuate the releasing mechanism of the main supply containers.

In such systems as above mentioned, the difficulty is sometimes encountered of having the pressure medium leak from the control container or 35 containers, so that the desired actuating force or pressure is not available when required. A much more effective system would be, therefore, one in which the desired operating pressure is built up at the exact moment when required.

It is accordingly an object of the present invention to provide a fire extinguishing apparatus 40 in which the fire extinguishing medium is stored in a plurality of containers, the releasing mechanisms of which are operated by a pressure developed at the time when it is desired to release 45 the fire extinguishing medium; and in this connection it should be noted that the use of a developed pressure which is independent of the pressure of the medium stored in the container is an important feature of the present invention, as it insures certainty of operation of the 50 entire system, even though a container or containers be empty by reason of the leakage of the pressure medium therefrom.

It is another object of the present invention to 55 provide fire extinguishing apparatus of the type

referred to with means for releasing the fire extinguishing medium under pressure during the incipient stage of a fire. More specifically, the invention contemplates that said means be arranged for operation by the expansive force of a 5 confined body of air, and in a preferred embodiment of the invention, that the confined body of air be vented to the atmosphere, a feature in itself already known, whereby the releasing apparatus can be designed to be unaffected by normal 10 changes in the temperature of the surrounding atmosphere, but to become immediately operative upon abnormal changes in temperature such as accompany an incipient fire.

It is a further object of the present invention 15 to provide a system for releasing pressure fluid from a plurality of containers thereof, either simultaneously or substantially simultaneously, utilizing a relatively small pressure developed by a heat actuator to actuate a pressure developing 20 unit and employing a pressure developed by the pressure developing unit upon operation of said heat actuator and independent of the pressure of the fluid stored in said container to release one or more of the remainder of the plurality of containers. 25

It is another object of the invention to provide 30 a fluid release mechanism of the above character, wherein the elements of the releasing device are so designed as to be capable of manual re-setting without difficulty and further to be insensitive to jars or other disturbing stresses while being highly sensitive to a predetermined actuating force.

As a further object of the invention, it is pro- 35 posed to provide an automatic safety mechanism which will prevent the actuation of the main container if the pressure in any of the supply containers becomes excessive by reason of tem- 40 perature rise while the discharge of the extin- guishing medium is not needed.

Other objects of the invention will appear as the description proceeds and reference will now be had for a more detailed description of the invention to the accompanying drawings forming 45 a part hereof, wherein:

Figure 1 is a view in side elevation of a fire extinguishing system constructed in accordance 50 with the present invention.

Figure 2 is a view in transverse section showing a fluid releasing mechanism constructed in accordance with the present invention.

Figure 3 is a view of the lever chamber of the releasing mechanism shown in Figure 2, the cover 55 of the lever chamber being removed.

Figure 4 is a view in section taken on line 4—4 of Figure 2 and looking in the direction of the arrows, the lever chamber not being shown.

In Figure 1 of the drawings is shown a plurality of pressure medium containers 1, each having a fluid releasing mechanism 2, each of the fluid releasing mechanisms being connected by a branch conduit 3 to a common delivery conduit 4. Each of the fluid releasing mechanisms 2 is provided with a chamber 5 containing means operable by the flow of a fluid for releasing the respective fluid releasing mechanisms, the chamber 5 being connected by branch tube 6 to pressure transmitting tubing 7, which latter is connected to one end of a pressure developing chamber 8. Within the pressure developing chamber 8 is arranged a piston member 9 having a piston rod 10 extending exteriorly of the chamber 8 through an opening provided in the cover member 11 of the chamber. On the upper end of the piston rod 10 is arranged a relatively heavy weight 12 designed to cause downward movement of the piston 9 and to develop in the chamber 8 a pressure sufficient to actuate the releasing means in the chambers 5 of the fluid releasing mechanisms 2. The weight 12 is normally held from descending by a cable 13 provided with a knob 14 supported on a releasable lever 15 of an air operated release mechanism 16, which latter may be in accordance with United States Letters Patent No. 1,269,556. The air operated release mechanism 16 in turn is connected by pressure transmitting tubing 17 to a heat actuator member 18, which may be of any suitable construction for use with the release mechanism 16.

Referring now to Figure 2 of the drawings, a supply of a medium under pressure is maintained in a container 1 by means of a closure body 19 and a bonnet 20. An adapter 21 serves to maintain the bonnet upon the closure body, the latter being threaded into the top of the container 1 and being provided with a frangible disc 22 secured in position by a nut 23. A cutter 24 is movable within the nut 23 and the adapter 21 is provided with threads 25 which engage co-operating threads formed on the closure body 19, threads 26 also being provided at the upper extremity of the adapter for engaging co-operating threads formed upon the bonnet 20.

Axially movable within the bonnet is a cutter stem 27 which is formed with a flange 28 having a close-working fit on its circumferential surface with the bore of the bonnet. An outlet 29 is provided in the bonnet for receiving a fitting 30 which is adapted to be connected to a branch conduit 3. The flange 28 on the cutter stem is preferably disposed so as to be nearer the container 1 than the outlet 29, as described in further detail hereinafter.

Before the cutter stem is assembled in the bonnet 20, a cup leather 31 is passed over the upper portion of the stem and seated by a spring 32 which provides the actuating force for moving the cutter and cutter stem toward the container. The spring 32 is seated against a nut 33 which is a combined sealing and re-setting nut, a stop 34 being provided on the upper end of the stem to limit the movement of the stem toward the container.

Wing indicators 35 are hinged to the nut at 36 and the above described mechanism constitutes the indicating mechanism to apprise an inspector as to the condition of the apparatus.

The above described cutter stem assembly is

inserted in the bonnet 20 and the combined sealing and re-setting nut 33 is run into position by means of threads 37 on the bonnet and nut.

Before the adapter 21 is coupled to the closure body 19, it is secured to the bonnet 20, a leather washer 38 being passed over the end of the cutter stem and secured in position by means of a nut 39 having threads 40 which engage the co-operating threads on the adapter 21. The cutter 24 is then secured to the lower end of the cutter stem 27 by means of a coupling nut 41 which is provided with threads 42 engaging co-operating threads on the cutter stem.

In the above described mechanism, the hollow cutter communicates with the hollow portion 43 of the cutter stem, which hollow portion communicates with the atmosphere by means of openings 44 formed in the upper end of the cutter stem. The cutter, adapter, and co-operating securing elements constitute no part of the present invention, although the cutter stem and wing indicating construction, as well as the means for providing communication between the hollow cutter and the atmosphere, are highly useful in connection with apparatus of the type herein provided.

The normal position of the cutter stem is as shown in Figure 2, the stem being shown in its upper position, the cutter 24 lying some distance above the frangible disc and the openings 44 communicating with the space under the wings. In this fashion, the pressure medium will be discharged into the atmosphere through the cutter 24, cutter stem, and openings 44 when the frangible disc is ruptured due to an excessive pressure of the medium within the container 1.

A flange 45 is formed on the cutter stem and serves as a catch, this flange being engaged by a suitable trigger releasing mechanism described in detail hereinafter. Extending within the bonnet 40 is a spindle 46 which is formed with a groove 47 for engaging the flange 45 on the cutter stem. The spindle is pivoted in the bonnet at 48 and extends externally thereof within the lever chamber 5.

The foregoing description relates to the disc rupturing mechanism and means for discharging the contents of a fluid container into a pipe line or, in the event that the discharge is accidental, into the atmosphere without possibility of any of the fluid entering the pipe line. The means for releasing the foregoing mechanism will now be described and, in the connection, it will be observed that the spindle 46 extends within the lever chamber 5 and has secured to the end thereof a lever 49. A contact roller 50 is provided on the upper end of the lever 49 and is adapted to engage a co-operating contact surface on one arm 51 of a bell crank lever having a depending arm 52. A stud 53 pivots the bell crank lever 51—52, and a contact roller 54 is formed on the lower extremity 60 of the depending arm 52. This last named contact roller is adapted to be engaged by a co-operating surface on arm 55 of a bell crank lever having an upwardly extending arm 56 and pivoted upon a stud 57. The arm 55 is further provided with an ear 58 upon the lower portion of which a camming surface 59 is formed sloping rearwardly from the lower edge of the ear, as viewed in Figure 3, the construction being further shown in Figure 2.

To normally restrain the second bell crank lever from disengaging the depending arm 52, a catch 60 is provided which engages the camming surface 59. The catch 60 is in the form of a contact roller carried by a lever 61, which is pivoted

at 62. The catch 60 of the tripping lever is normally urged into engagement with the surface 59 of the second bell crank lever by means of a spring 63.

5 To effect the releasing movement of the tripping lever 61, a paddle 64 is formed thereon said paddle being arranged to cover a nozzle opening 65 connecting with a passage 66 formed in the wall of the lever chamber 5. A suitable fitting 67 connects the passage 66 with the branch tube 6, which in turn connects with the pressure transmitting tubing 7, as already described in connection with Figure 1. A thin disc 68 of felt or other soft material is secured to the end of the paddle 64 so as 10 to normally overlie the nozzle opening 65. This disc 68 permits the covering of the nozzle opening 65 without interfering with the setting of the lever system, as the disc 68 yields under the force exerted by the spring 63.

20 When, therefore, a fire occurs, the heat of the fire expands the air normally confined in the heat actuator member 18, the pressure developed therein being transmitted through the pressure transmitting tubing 17 to the release device 16, which 25 is thereby operated to release the weight 12. The weight 12, being released, causes descent of the piston 9 in the pressure developing chamber 8, building up a pressure in the chamber 8 which is transmitted through the pressure transmitting 30 tubing 7 and the branch tube 6 to the nozzle openings 65 of the respective lever chambers 5, whereby the flow of the fluid directed against the paddles 64 causes the levers 61 to rotate to disengage the roller catches 60 from the lever systems 35 in the respective lever chambers 5. Upon disengagement of a tripping lever 61 from the camming surface 59 of a second bell-crank lever, the second bell-crank lever is free to rotate in a counter-clockwise direction, as viewed in Figure 3. 40 In this fashion, the roller contact 56 of the depending arm 52 is disengaged and the first bell-crank lever partakes of a clockwise movement; as viewed in Figure 3. Arm 51 of the first bell-crank lever thus disengages the contact roller 50 and 45 permits spindle 46 to turn under the force exerted by spring 32 to disengage groove 47 from the flange 45. Such disengagement permits the cutter 24 to be advanced into the disc 22 and effects the rupturing thereof, simultaneously moving the openings 44 to communicate with the region within the nut 33 and the bonnet 20 and thus causing the discharged medium to flow into the branch conduit 3.

In order to release the apparatus manually, 55 there is provided, as shown in Figure 1, an operating rod 69 having an operating handle 10. The operating rod 69 is connected to a lever 71 mounted on the release device 16 in such a position that, upon upward movement of the operating 60 rod 69, the lever 71 rotates to mechanically force the knob 14 off the restraining lever 15, thus permitting the weight 12 to descend in the manner already described.

From the foregoing description it will be seen 65 that my present invention embodies the important objects pointed out at the beginning, and while the invention resides in certain principles of construction and operation which have been illustrated and described in connection with the 70 accompanying drawings, it will be apparent to those skilled in the art that they can, of course, be embodied in other forms of construction without departure therefrom, and I do not wish to be strictly limited for this reason to the disclosure, 75 but rather to the scope of the appended claims.

I claim:

1. In a releasing device for releasing a medium from a container in which the medium is stored under pressure, the combination of a body member to be secured to the container, a frangible disc carried by the body member and confining the medium within the container, a cutter stem movable in the body member, a cutter on the stem to rupture the disc, a spring normally urging the cutter toward the disc, a spindle rotatably mounted in the body member, a catch on the cutter stem engaging the spindle, releasable means normally preventing movement of the spindle, said releasable means comprising a series of interengaging levers mounted on the body member and adapted to move into disengagement when the levers are released, the outermost lever of said series being secured to the spindle, a tripping lever for holding the innermost lever of the series against the transmitted force of the spring normally urging the cutter toward the disc, and means to direct a flowing fluid against said tripping lever, so as to trip it to permit release of the series of levers.

2. In a releasing device for releasing a medium from a container in which the medium is stored under pressure, the combination of a body member to be secured to the container, a frangible disc carried by the body member and confining the medium within the container, a cutter stem movable in the body member, a cutter on the stem to rupture the disc, a spring normally urging the cutter toward the disc, a spindle rotatably mounted in the body member, a catch on the cutter stem engaging the spindle, releasable means normally preventing movement of the spindle, said releasable means comprising a series of interengaging levers mounted on the body member and adapted to move into disengagement when the levers are released, the outermost lever of said series being secured to the spindle, a tripping lever for holding the innermost lever of the series against the transmitted force of the spring normally urging the cutter toward the disc, means terminating in a discharge outlet to direct a flowing fluid adjacent said tripping lever, and a paddle-like element formed on said tripping lever and positioned adjacent said discharge outlet and in the path of flow of fluid therefrom, whereby the flowing fluid will act on the paddle-like element to trip the tripping lever.

3. In a releasing device for releasing a medium from a container in which the medium is stored under pressure, the combination of a body member to be secured to the container, a frangible disc carried by the body member and confining the medium within the container, a cutter stem movable in the body member, a cutter on the stem to rupture the disc, a spring normally urging the cutter toward the disc, a spindle rotatably mounted in the body member, a catch on the cutter stem engaging the spindle, releasable means normally preventing movement of the spindle, said releasable means comprising a series of interengaging levers mounted on the body member and adapted to move into disengagement when the levers are released, the outermost lever of said series being secured to the spindle, a tripping lever for holding the innermost lever of the series against the transmitted force of the spring normally urging the cutter toward the disc, means terminating in a discharge outlet to direct a flowing fluid adjacent said tripping lever, a paddle-like element formed on said tripping lever and substantially overlying said discharge outlet, and compressible means carried by said

paddle-like element and overlying said discharge outlet and normally sealing the latter, whereby the flowing fluid will act on the paddle-like element to trip the tripping lever.

- 5 4. In a release device for fluids under pressure having a frangible disc to confine a medium under pressure, a body member provided with an outlet, a cutter movable in the body to rupture the disc, a spring to urge the cutter normally toward the disc, a rotatable spindle in the body releasably engaged by the cutter to normally prevent movement of the cutter, an arm on the spindle having a pressure surface, pivotally mounted restraining means movable into and out of engagement with the pressure surface of the spindle arm to prevent movement thereof, and means to release the restraining means comprising means to direct a flowing fluid against an element of the restraining means to release the restraining means.
- 10 5. A system for releasing a medium from a plurality of containers in which the medium is stored under pressure through the medium of the relatively small expansive force of a confined body of fluid, comprising restraining means operable by the expansive force of a confined body of fluid, medium releasing means for each container, each comprising a frangible disc to confine the medium within the container, disc rupturing means for rupturing the frangible disc to release the medium, and means operable by the flow of a fluid to effect operation of the disc rupturing means; and means operable upon release of the restraining means to generate a pressure greater than that developed by the confined body of fluid to obtain the desired force to create the fluid flow for operating the disc rupturing means of a plurality of containers.
- 15 6. A system for releasing a medium from a plurality of containers in which the medium is stored under pressure through the medium of the relatively small expansive force of a confined body of fluid, comprising restraining means operable by the expansive force of a confined body of fluid, medium releasing means for each container, each comprising a frangible disc to confine the medium within the container, disc rupturing means for rupturing the frangible disc to release the medium, and means operable by the force of a fluid to effect operation of the disc rupturing means; and means operable upon release of the restraining means to generate a pressure greater than that developed by the confined body of fluid to obtain the desired force to operate the disc rupturing means of a plurality of containers.
- 20 7. A system for releasing a medium from a plurality of containers in which the medium is stored under pressure through the medium of a relatively small operating force, comprising restraining means operable by a relatively small operating force, medium releasing means for each container, each comprising a frangible disc to confine the medium within the container, disc rupturing means for rupturing the frangible disc to release the medium, and means operable by the force of a fluid to effect operation of the disc rupturing means; and means operable upon release of the restraining means to generate a force

greater than the relatively small operating force to obtain the desired force to operate the disc rupturing means.

8. In a system for releasing a medium from a plurality of containers in which the medium is stored under pressure and in which each container is provided with a medium releasing device comprising a body member to be secured to the container, a frangible disc carried by the body member and confining the medium within the disc, a cutter stem movable in the body member, a cutter on the stem to rupture the disc, a spring normally urging the cutter toward the disc, a spindle rotatably mounted in the body member, a catch on the cutter stem engaging the spindle, releasable means normally preventing movement of the spindle, said releasable means comprising a series of interengaging levers mounted on the body member and adapted to move into disengagement when the levers are released, the outermost lever of said series being secured to the spindle, a tripping lever for holding the innermost lever of the series against the transmitted force of the spring normally urging the cutter toward the disc, and means operable upon a change in a normal fluid pressure to release said tripping lever, a chamber apart from said medium releasing devices and alterable in volume by movement of a wall thereof to compress the fluid within the chamber, means to effect movement of the wall of the chamber, and means defining a fluid conducting path from said chamber to each of said means operable upon a change in a normal fluid pressure.

9. In a system for releasing a medium from a plurality of containers in which the medium is stored under pressure and in which each container is provided with a medium releasing device comprising a body member to be secured to the container, a frangible disc carried by the body member and confining the medium within the disc, a cutter stem movable in the body member, a cutter on the stem to rupture the disc, a spring normally urging the cutter toward the disc, a spindle rotatably mounted in the body member, a catch on the cutter stem engaging the spindle, releasable means normally preventing movement of the spindle, said releasable means comprising a series of interengaging levers mounted on the body member and adapted to move into disengagement when the levers are released, the outermost lever of said series being secured to the spindle, a tripping lever for holding the innermost lever of the series against the transmitted force of the spring normally urging the cutter toward the disc, and means to direct a flowing fluid against said tripping lever, so as to trip it to permit release of the series of levers, a chamber apart from said medium releasing devices and alterable in volume by movement of a wall thereof to compress the fluid within the chamber, means to effect movement of a wall of the chamber, and means defining a fluid conducting path from said chamber to each of said means for directing a flowing fluid against a tripping lever.

DANIEL MAPES.
